UNITED STATES PATENT OFFICE.

CHRISTOPHER C. SHELBY, OF NEW YORK, N. Y.

BUCKLE.

SPECIFICATION forming part of Letters Patent No. 330,518, dated November 17, 1885.

Application filed August 22, 1885. Serial No. 175,084. (No model.)

To all whom it may concern:

Be it known that I, CHRISTOPHER C. SHELBY, a citizen of the United States, and a resident of New York, in the county of New York and 5 State of New York, have invented certain new and useful improvements in Buckles, of which the following is a specification.

My present invention relates to buckles for suspenders and for other purposes, and its 10 primary object is to facilitate the production of the buckle and reduce the cost of its manufacture.

When the several parts of the buckle are prepared according to my present invention, 15 they may be assembled very quickly and without the exercise of much skill.

It is also an object of my invention to improve the locking-lever plate so as to render more secure the locking of the webbing in the 20 buckle.

The features of novelty for which I desire protection are pointed out in the claims at the end of this description.

In the accompanying drawings, which form 25 part of this description, and in which like parts are indicated by like letters, Figure 1 is a top plan view of a buckle-blank constructed according to my invention. Fig. 2 is a view in elevation of the double-headed pin which 30 constitutes the axis of the lever-plate. Fig. 3 is a perspective view showing the under face of the completed buckle with the lever-plate elevated, so as to more fully expose its construction; and Fig. 4 is a top plan view 35 showing the lever plate, having pin D secured to its top instead of to its under surface, as in Fig. 3.

Referring to the drawings, the letter A is the buckle-frame, which may be of any suitable material, and may have upon its exposed 40 surface any desirable ornamentation. B is the usual tongue for securing the suspender-ring—for instance, in position when it has been caught over the turned-up projection C.

45 The letters a a indicate wings at the sides of the blank, which are adapted to be bent up to furnish bearings for the axis of the lever-plate. As thus described, this blank is not unusual; but in the process of stamping it out I arrange 50 the tool to cut the ears at the points b b, for a purpose presently explained.

The pin D, which is the axis upon which the

lever-plate turns, is prepared with heads at both ends, as shown. The lever-plate E is 55 preferably of the form shown, and it has secured to either its upper or under surface the double-headed pin D. In Fig. 4 said pin is shown secured to the upper surface of plate E, while in Fig. 3 it is secured to its under surface. In both cases the connection of the pin 60 to the plate is effected expeditiously by cutting back small portions of the inner edge, c, of the plate and turning up the cut portions d securely around the pin D, as shown in both 65 of the views referred to. The inner edge, c, of the lever-plate is at right angles to the body of said plate, and is designed, when the lever-plate is turned down upon the webbing, to hold the webbing from slipping through the buckle. This feature is an old one. 70

A peculiarity of my lever-plate lies in bending its front or outer edge, e, at right angles to its body, so that when the plate is locked on the webbing the said front edge will bind 75 the webbing, and that more firmly as the webbing is drawn upon. A small portion of this bent front edge, e, is turned up at e', in order to furnish facility for lifting the lever-plate with the thumb-nail when it is desired to shift the position of the webbing in the buckle. 80

The lever-plate, constructed in the manner explained, and having the pin D secured thereto, as shown and described, is affixed to the buckle-blank A, as follows: In the first place the buckle-blank itself is prepared by binding 85 over the projection C, so that its end will just cover the spring-tongue B, in the usual manner, and its wings a a are bent up at right angles to the main portion of the blank, as shown in Fig. 3. In this condition the blank 90 is ready to receive the lever-plate E, which is secured in position by pressing inward the ears b b, so as to permit the heads of the pin D to pass through the openings from which the ears b have been pressed. When the axis of 95 the lever-plate has been properly adjusted, the ears are pressed back and their ends locked under the heads of the pin D, as shown in Fig. 3. This method of construction avoids the necessity of heading the pin after it has been 100 inserted in its bearings.

Having thus described my invention, what I claim as new is—

1. The buckle-frame having ears b, punched

therefrom, as explained, in combination with the lever-plate having secured thereto the double-headed pin D, which pin is held in position by the ears b, bearing upon the inner surfaces of its heads, substantially as set forth.

2. A buckle consisting of the frame A, having ears b, lever-plate E, having its front edge formed at right angles to its body, and double-headed pin D, the whole constructed and operating substantially as set forth.

3. A buckle consisting of the frame A, having ears b, lever-plate E, having its front and rear edges formed at right angles to its body, and double-headed pin D, the whole construct-

ed and operating as and for the purpose described.

4. A buckle having a lever-plate whose front edge is formed at right angles to its body, said front edge being provided with a thumb-notch, substantially as set forth.

Signed at New York, in the county of New York and State of New York, this 21st day of August, A. D. 1885.

CHRISTOPHER C. SHELBY.
